UNITED STATES PATENT OFFICE

101,710

DESIGN FOR A DESK TRAY

Rachel F. Patterson, Pittsburgh, Pa., assignor to Heppenstall Company, Pittsburgh, Pa., a corporation of Pennsylvania

Application September 10, 1936, Serial No. 64,793

Term of patent 14 years

To all whom it may concern:

Be it known that I, Rachel F. Patterson, a citizen of the United States, residing at Pittsburgh, in the county of Allegheny and State of Pennsylvania, have invented a new, original and ornamental Design for a Desk Tray, of which the following is a specification, reference being had to the accompanying drawing, forming a part thereof.

Fig. 1 is a perspective view of a desk tray, showing my new design; and Fig. 2 is a top plan view thereof.

I claim:

The ornamental design for a desk tray, as shown.

RACHEL F. PATTERSON.
